LEVELING DEVICE

Paul S. Stevens, South Milwaukee, Wis., assignor
to Bucyrus-Erie Company, South Milwaukee,
Wis., a corporation of Delaware

Application October 16, 1936, Serial No. 105,888

12 Claims.

(Cl. 280—6)

My invention relates to new and useful improvements in leveling devices, and more particularly to leveling devices for large power excavators, which have four independent sets of caterpillar traction, one of which is mounted at each of the four corners of the base; each set supporting its corner of the base by means of an electrical, mechanical, or hydraulic jack. It is desired to control the automatic action of these jacks, by means of a level-responsive controlling device.

But leveling is not the only problem involved in this connection. Due to unevenness of the ground, it has been found necessary to automatically equalize the pressure on the four jacks. Also it has been found necessary to prevent any jack from overrunning predetermined extreme in or out positions. Optional manual control for each jack has also been found advisable.

Accordingly it is the object of my invention to provide a system of four jacks, which shall level automatically and equalize automatically, which shall optionally be controllable by the operator, and in which no jack can overrun.

A further object of my invention is to improve the details of each of these functions.

In addition to my principal object, above stated, I have worked out a number of novel and useful details, which will be readily evident as the description progresses.

My invention consists in the novel parts, and in the combinations and arrangements thereof, which are defined in the appended claims, and of which one embodiment is exemplified in the accompanying drawings, which are hereinafter particularly described and explained.

Throughout the description, the same reference number is applied to the same member or to similar members.

Figure 1 is a perspective view, partly cut away, of the base of an excavator possessing a leveling system which includes the device of my invention.

Figure 2 is a vertical section of one of my jacks.

Figure 3 is an enlarged elevation of my equalizing switch.

Figure 4 is an enlarged elevation of one of my limiting switches.

Figure 5 is an electric-wiring diagram of my complete invention.

Referring now to Figure 1, we see that 11 is the main base of the excavator or other machine, to which it is intended to apply my invention. This base is supported, by means of four hydraulic jacks 12, on four caterpillar trac-

tion ground-engaging units 13, which may be propelled by any convenient means, not shown.

Associated with each jack, there is a pump P, driven by a motor M, and certain valves (not shown in Figure 1), all of which are operated and controlled through certain electric interlocks which will be hereinafter described.

Figure 1 is quite diagrammatic. Turning now to Figure 2, it will be seen that each traction unit 13 supports a piston 14 through a universal joint 15. Piston 14 operates in cylinder 16, the operating fluid being admitted to the space 17. The piston 14 is shouldered, as indicated at 18, so that when, relative to the cylinder 16, the piston is forced downward far enough for the shoulder to abut element 19, the piston 14 and the cylinder 16 will be prevented from separating further. This extreme position of the piston with respect to the cylinder is shown by dotted lines.

Rigid with the top of the cylinder is an element 20, having a convexly curved upper bearing surface, which cooperates with the concave under surface of a bearing element 21, which is rigidly carried by a casting 22 attached to the main frame 11. Aligned through bearing elements 20 and 21 and casting 22 is a hole for the passage of bolt 23, which is inserted into the head of cylinder. The hole through these three elements is made somewhat larger than the bolt 30, so that there shall normally be a small clearance 24 at each side of the bolt. A similar small clearance 25 is shown between the lower portion of the cylinder 16 and the lower plate of the main frame. The purpose of these clearances is to allow a slight lateral swing of the cylinder with respect to the main base 11. Thus the cylinder is not rigidly connected to the base 11, its only connections being the bolt 23 and a brace (not shown) below the base, said brace being also capable of allowing a small motion of the cylinder.

The upper end of bolt 23 is provided with a nut 26 and a lock nut 27. These are so adjusted that, when the curved bearing surfaces of elements 20 and 21 are in contact, there is a small clearance 28, of the order of one quarter inch, between the nut 26 and its seat on casting 22. The function of this clearance, which will be explained in detail later, is intimately connected with the equalizing switch 29, which is attached by a bracket 30 to the under side of the lower plate of the main base 11.

Figure 3 shows this equalizing switch considerably enlarged. Cylinder 16 carries a small

lug 31, upon which rides a wheel 32. The wheel is carried by the small arm of a bell crank 33, whose pivot is carried by bracket 30. To the end of the long arm of bell crank 33 is pivoted a link 34, whose other end is pivoted to the crank 35. The different lengths of the two arms of bell crank 33 cause a small motion of wheel 32 to effect a large motion of the crank 35. Rigid with this crank, but inside the box, is the moving arm which opens or closes the equalizing switch, according as lug 31 pushes wheel 32 upward or allows the wheel to move downward. The inner construction of this switch, being well known, is not shown. Normally, when the main base 11 is resting on the cylinder, wheel 32 is in its extreme upward position, and the switch is open. If, owing to a slight sinking of traction unit 13, the clearance 28 closes, lug 31 sinks. A spring (not shown) within the box of switch 29 compels the wheel 32 to follow lug 31, and closes the switch.

Attached to a convenient part of the traction base 13, as at 36, Figure 2, is a wire rope 37 which passes through a hole 38 in the lower plate of main base 11, to a pulley 39 supported by the upper plate of the base 11, and thence to a switch-actuating weight 40. This weight slides on a vertical guide 41, and serves to actuate limit switches 42, 43 and 44, which are placed as follows. Limit switch 42 is positioned so as to be actuated by the weight 40 when the piston is quite near, but not at, its "all out" position; that is, when the particular corner of main base 11 is almost as far above traction unit 13 as possible. Limit switch 43 is so positioned that it will be contacted by the weight 40 only when the piston is at its "all out" position, and main base 11 is as far above traction unit 13 as the mechanical construction allows. Limit switch 44 is so positioned that it will be actuated only when the piston is at its "all in" position; that is, when the particular corner of main base 11 is as near the traction unit 13 as the mechanical construction will allow.

Switch 42 is shown enlarged in Figure 4. A wheel 45 is carried on an arm 46 pivoted at 47. In rigid relation to arm 46 but inside the box is the moving arm which closes the switch when wheel 45 is contacted by the sliding weight 40. Switch 42 is therefore a "normally open" switch. Switches 43 and 44 are similar to switch 42, except that they are "normally closed" switches, and are open only when contacted by sliding weight 40.

The inner mechanism of these switches is well known and therefore not shown. Each contains a spring, to restore it to "normal" position, when it is not contacted by the weight 40.

Turning now to Figure 1, I shall consider the lower left hand corner of the main base as corner 1, the remaining corners being numbered counter-clockwise around the figure. For the proper understanding of the electrical hook-up, as shown on Figure 5, it is essential to remember that corner 3 is diagonally opposite to corner 1, and that corner 4 is diagonally opposite to corner 2.

At the right hand margin of Figure 5, I have placed opposite certain of the electrical instrumentalities the capital letters: A, B, C, D, E, F, G, H, J. Each of these letters refers collectively to the instrumentalities that are to be found across the page on a level with the particular capital letter. All the instrumentalities opposite to any one letter are of the same kind.

The diagram naturally divides itself into four vertical bands, each associated with a motor-

pump set, and the motors and pumps are numbered accordingly, the numbering corresponding to the numbering of the corners, as stated above.

With the exception only of the E, G, and J elements, all the devices which are shown (Figure 5) in the vertical band which includes M1 and P1, more particularly relate the corner 1 and therefore will be actually located at that corner; and similarly for the other vertical bands. Therefore when it becomes necessary to specify an individual one of the lettered devices, its number will be added to the capital letter.

Thus if Figure 2 represents the assembly at corner 1,

A1 is the limit switch 44 of corner 1.

B1, the left hand one of the pair, is limit switch 43 of corner 1.

B1, the right hand one of the pair, is limit switch 42 of corner 1.

C1 is a solenoid which actuates a bleeder (not shown), to bleed cylinder 14 of corner 1 into a sump.

D1 is a magnetic switch to actuate the motor-pump system at corner 1.

E represents manual controls, located at the operator's station, their use to be explained later.

F1 is limit switch 29 of corner 1.

The function of the G and H switches will be stated later.

The J elements are four mercury switches, arranged in pairs, the two elements of each pair being held in fixed relation to each other, though the pair may be tilted either way as a unit. These 35 depart from the numbering system used above, in that, beginning at the left, the individual switches must be numbered J1, J3; J2, J4.

The pair of switches, J1—J3, comprise a switch unit used to bring corners 1 and 3 to the same 40 level. They might be merely rigidly set on the main base in the diagonal between those corners, but in that case, because of the shortness of the individual elements, it would require a very considerable difference of level to cause them to 45 function at all. Therefore I make use of the device shown and described in the copending application of Luther E. Blanchett for improvements in leveling devices, filed May 13, 1936, Serial No. 79,594, which is owned by my assignee. This 50 device, by multiplying the difference of level of the ends of a much longer "base line", set in the line between corners 1 and 3, will tilt my mercury switch unit, J1—J3, into operative position, for a difference of level of only a few inches between 55 corners 1 and 3.

The switch unit, J2—J4, is similarly arranged with respect to the diagonal from corner 2 to corner 4.

The single heavy line 51 represents the three-phase power line to the motors. The control system is supplied with power through wires 52 and 53, respectively at top and bottom of diagram.

A switch 54, when open, will entirely cut out the automatic control, leaving the manual control still available.

First, suppose that all pistons are initially at their mid-positions, and that corner 1 is lower than its opposite corner 3, corners 2 and 4 being level. This will tilt downward the left end of 70 mercury switch unit, J1—J3, thereby allowing current to pass from 53 successively through switch 54, mercury switch J1, solenoid 55, wires 56, 57, 58 to wire 52. Solenoid 55 will close the triple-pole switch H1, thereby sending current 75.

through wire 59 and the left hand one (43) of the B1 switches, to wire 52; and closing magnet switch D1, thereby starting pump P1. At the same time, current will flow through the central switch point of H1, and wires 60, 61, 62, thereby actuating the solenoid C3, which will open a valve to bleed the cylinder at corner 3 into a sump. Neither the valve nor the sump is shown, they being of any convenient conventional form, and not constituting per se an inventive feature. These two actions will raise corner 1 and lower corner 3. When level is attained, mercury switch unit J1—J3 will again be in normal position, and consequently solenoid 55 will be deenergized, and H1, which is a spring switch, will open, and pumping and bleeding will stop.

Now let us assume that the excavator is still not level, although P1 has pumped the jack at corner 1 almost to its limit of travel. It is obvious that the excavator cannot be leveled further without lowering both corners 2 and 4. My invention automatically accomplishes this in the following manner.

Referring to Figure 2, we see that, in this case, as the cylinder 16 is forced upward with respect to the piston 14, the rising of the frame 11 at this corner will raise pulley 39; and, inasmuch as attachment 36 remains down, there will be a pull on rope 37, which will raise weight 40 with respect to frame 11. The weight 40 will first contact switch 42, which is the right hand one of the B1 switches in Figure 5, thereby closing it.

The closing of the right hand B1 switch (42) will energize C4 solenoid valve, thereby bleeding corner 4. As corner 3 is still bleeding, the side 3—4 of the excavator will be lowered. When corner 4 is sufficiently below the level of opposite corner 2, the mercury switch unit J2—J4 will be tilted into position to cause J4 to close the circuit through H4 and D4. This will set M4 and C2 into action, thereby pumping at corner 4 and bleeding at corner 2. We are now both pumping and bleeding at corner 4, but the corner will remain at the same position, as the valves bleed at about the same rate as the pumps supply liquid.

When corner 2 reaches the level of corner 4, mercury switch unit J2—J4 will return to its normal position, opening H4 and discontinuing pumping by P4. Then leveling between corners 1 and 3 will continue as described above.

If corner 1 was originally a large amount below level, the complete cycle described above will be several times repeated.

If the above described action, resulting from the closing of switch 42, has not relieved the situation which closed this switch, namely the fact that the jack at the corner in question had been pumped almost to the limit of its travel, I provide the following safety device as a last resort. Further pumping of that jack results in further raising the weight 40 until it contacts switch 43, which is the left hand one of the B1 switches, thereby opening it. This will stop pumping by P1, but will not stop bleeding at the other three corners, and hence will not interfere with the effect of the closing of switch 42, already described.

The means for accomplishing these two successive remedies, called into play by the successive closing of switch 42 and opening of switch 43, will be described in certain of my claims as means associated with each corner, whereby maximum expansion of the jack at any corner will first lower the base by releasing the jack at one of the corners adjacent to the given corner, and

will then put an end to the expansion of the jack at the given corner.

In the foregoing discussion of the action of my device when corner 1 is low, no account has been taken of the possibility that corner 3 may be in a completely bled position at the same time that switch 42, Figure 2, (the right hand one of the B1 switches of Figure 5) is closed. If corner 3 has bled to its limit, its piston is "all in", and the sliding weight, 40 at corner 3, will open switch 44, which is switch A3 of Figure 5, and corresponds, at corner 3, to switch 44 at corner 1, shown in Figure 2. This will prevent the bleeding of C4, and the consequent lowering of corner 4 in spite of the fact that switch B1 right is still closed. The object of this is that, inasmuch as corner 1 (which is low) has been raised as far as possible, and as corner 3 (which is high) has now been lowered as far as possible, no further leveling along that diagonal is attainable, and hence we do not wish to render the cross diagonal wobbly (by bleeding either of its jacks) to no good end.

This reaching the limit of possibility of further leveling, is not a defect of my invention; for obviously any leveling-device, which could be humanly designed, must of necessity have a limit beyond which it cannot function further.

It should be noted that this opening of switch 44 under the circumstances stated, then prevents merely such bleeding on the 2—4 diagonal as would normally be caused by lack of level of the 1—3 diagonal, and does not at all prevent bleeding on the 2—4 diagonal responsive to its own lack of level.

From all the foregoing discussion, it will be seen that, in order to simplify my electrical hook-up, I have provided a system which, in many cases, will operate circuitously through many cycles, before finally attaining a position of rest. The advantage of simplicity of construction, however, outweighs circuitry of operation.

But, by the addition of an optional manual control, I can enable the operator to rapidly perform the first rough leveling operations by eye, after for example glancing at a spirit level; leaving it to my automatic controls to finish up the job in a minimum of cycles.

To this end, I have provided an optional manual control entirely independent of the automatic control. The eight similar elements on the E line, Figure 5, represent push-buttons. Following from wire 53, through wires 63 and 64, it will be seen that if button 65 is pushed, M1 will be actuated and P1 will pump corner 1. If button 66 is pushed, solenoid C1 will bleed corner 1. It is to be noted that wire 63 takes power, regardless whether main switch 54 is open or closed.

The push buttons will also be of use in many circumstances that readily suggest themselves. All the foregoing falls under the generic term: "leveling". I shall now discuss what I call "equalizing".

In case corner 1 is originally relatively high, and has been bled to its limit before corner 3 is pumped up to its limit, the continued pumping of P3 will tend to raise the main base off the cylinder at corner 2 or corner 4, thus causing what I shall call in my claims the "dangling" of the jack at that corner. This dangling will cause the entire jack to drop as far as permitted by the small clearance 28 at the corner where the dangling occurs, thereby closing the corresponding equalizing switch 29' (as shown at F2 and F4 in Figure 5). As F2 and F4 are in parallel,

the closing of either of them will close the right hand G switch, 67. Current will therefore flow via wires 68, 69, to switch 67, where it divides. One line, via wires 70 and 71 will start pump P2; 5 and the other, via wire 72, will start pump P4. Then, as soon as the clearance 28 is open again (provided the corresponding clearance paired with it has not, in the meantime, closed), the F switch, 29, will open, and pumping at corners 2 and 4 will stop. During and after all this pumping 10 the process of leveling between corners 1 and 3 will automatically continue until completed.

The equalizing by means of switch 29 also comes automatically into play whenever, by reason of heavy digging over one corner, or for any 15 other reason, a corner sinks an amount sufficient to cause an undesirable teetering of the excavator, but not enough to actuate the corresponding mercury switch.

20 My discussion has, for simplicity, been predicated upon the assumption that corner 1 was initially too low, and corner 3 initially too high; thus calling for the expansion of the jack at corner 1, and the contraction of the jack at corner 3. As the four "vertical bands" of Figure 25 5 plainly exhibit the symmetry of the circuits with respect to the four corners of the excavator, it is not considered necessary to discuss the consequences of any other unlevel condition.

30 Owing to the "capillary repulsion" between glass and mercury, the mercury switches will not close the circuits of which they constitute parts until there is a difference of level of at least three or four inches between two corners. This 35 is of advantage as it is not desirable that the mercury units be affected by ordinary vibrations. But the mercury connection having once been made, the cohesion of the mercury will maintain it until the difference of level is nearly zero.

40 Main switch 54, Figure 5, is arranged to be automatically opened when the machine is travelling, as it is not necessary to correct for every unevenness of the ground over which the machine is momentarily passing. The precise means 45 of this automatic opening is not claimed as inventive. Any mechanic or electrical engineer could readily devise means to this end, such, for example as solenoid switch 54 shown in Figure 5. The solenoid of this switch is actuated by being 50 in some electric circuit 73 which is energized during propelling.

In Figure 1, I have shown at 48, a pipe connecting the pipes which supply liquid from two adjacent pumps to their respective cylinders. This 55 pipe 48 has a valve 49, conventionally shown, which is automatically opened when the machine is travelling. This allows the four caterpillar units to accommodate themselves freely to unevennesses of the ground, with the load approximately equally distributed among them.

60 Although I have described my invention as used with hydraulic jacks, it is obvious that it can be equally well applied to a system using electrical or mechanical jacks.

65 And although I have described my invention with respect to four independent ground-engaging units, the term "ground-engaging unit" is to be understood as also comprising one end of a ground-engaging device, which device supports 70 the base through a jack at each end of such device.

When herein I refer to "equalizing the pressure" on the four jacks, I realize that I am not using this phrase in its literal physics sense.

75 Rather I mean so pressing the jacks against the

ground, with the main base level, that each jack will bear its normal share of the load, as the center of gravity and digging reactions shift from point to point during the digging cycle.

Having now described and illustrated one form 5 of my invention, I wish it to be understood that my invention is not to be limited to the specific form or arrangement of parts hereinbefore described, except in so far as such limitations are specified in the appended claims. 10

I claim:

1. In combination: a base; four ground-engaging units; four jacks, one connected to and supported by each ground-engaging unit, and connected to and supporting the base; means to expand each jack; means to release each jack, so as to permit it to contract; electric controls for the expanding and releasing of the jacks; two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners; and, with respect to each corner, means associated with that corner, whereby maximum expansion of the jack at the corner will first lower the base by releasing the jack at one of the corners adjacent to the given corner, and then will put an end to the expansion of the jack at the given corner.

2. In combination: a base; four ground-engaging units; four jacks, one connected to and supported by each ground-engaging unit, and connected to and supporting the base; means to expand each jack; means to release each jack, so as to permit it to contract; electric controls for the expanding and releasing of the jacks; two 40 level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners; and, with respect to each corner, means associated with that corner, whereby maximum expansion of the jack at the corner will lower the base by releasing the jack at one of the corners adjacent to the given corner, and will put an end to the expansion of the jack at the given corner.

3. In combination: a base; four ground-engaging units; four jacks, one connected to and supported by each ground-engaging unit, and connected to and supporting the base; means to expand each jack; means to release each jack, so as to permit it to contract; electric controls for the expanding and releasing of the jacks; two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners, with respect to each corner, means associated with that corner, whereby maximum expansion of the jack at that corner will lower the base by releasing the jack at one of the corners adjacent to the given corner, and will put an end to the expansion of the jack at the given corner; and means whereby

maximum contraction of the jack at the corner opposite to the given corner will render inoperative the first-mentioned effect of the last-mentioned means.

5 4. In combination: a base; four ground-engaging units; four jacks, one connected to and supported by each ground-engaging unit, and connected to and supporting the base; means to expand each jack; means to release each jack, so
10 as to permit it to contract; electric controls for the expanding and releasing of the jacks; two level-responsive switch devices, each responsive to the difference in level of a pair of opposite corners of the base; each switch device being so
15 coupled with the electric controls that a difference in level of a pair of opposite corners of the base will expand the jack at the lower of these two corners, and will release the jack at the higher of the two corners; and means whereby
20 the dangling of any jack, without contributing to the support of the base, will cause the expansion of that jack.

5. In combination: a base; four ground-engaging units; four jacks, one connected to and supported by each ground-engaging unit, and connected to and supporting the base; means to expand each jack; means to release each jack, so as to permit it to contract; electric controls for the expanding and releasing of the jacks;
- 25 30 two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners, with respect to each corner, means associated with that corner, whereby maximum expansion of the jack at that corner will lower the base by releasing the jack at one of the corners adjacent to the given corner, and will put an end to the expansion of the jack at the given corner; and means whereby the dangling of any jack, without contributing to the support of the base, will cause the expansion of that jack.
- 35 40 45

6. In combination: a base; four ground-engaging units; four jacks, one connected to and supported by each ground-engaging unit, and connected to and supporting the base; means to expand each jack; means to release each jack, so as to permit it to contract; electric controls for the expanding and releasing of the jacks; two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners, with respect to each corner, means associated with that corner, whereby maximum expansion of the jack at that corner will lower the base by releasing the jack at one of the corners adjacent to the given corner, and will put an end to the expansion of the jack at the given corner; means whereby maximum contraction of the jack at the corner opposite to the given corner will render inoperative the first-mentioned effect of the last-mentioned means; and means whereby the dangling of any jack, without contributing to the support of the base, will cause the expansion of that jack.

7. In combination: a base; four ground-engaging units; four jacks, one connected to and

supported by each ground-engaging unit, and connected to and supporting the base; means to expand each jack; means to release each jack, so as to permit it to contract; electric controls for the expanding and releasing of the jacks; two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners; and means automatically rendering all the foregoing means inoperative during propelling. 5 10

8. In combination: a base; four ground-engaging units; four jacks, one connected to and supported by each ground-engaging unit, and connected to and supporting the base; means to expand each jack; means to release each jack, so as to permit it to contract; electric controls for the expanding and releasing of the jacks; two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners, with respect to each corner, means associated with that corner, whereby maximum expansion of the jack at that corner will lower the base by releasing the jack at one of the corners adjacent to the given corner, and will put an end to the expansion of the jack at the given corner; means whereby the dangling of any jack, without contributing to the support of the base, will cause the expansion of that jack; and means automatically rendering all the foregoing means inoperative during propelling.

9. In combination: a base; four ground-engaging units; four jacks, one connected to and supported by each ground-engaging unit, and connected to and supporting the base; means to expand each jack; means to release each jack, so as to permit it to contract; electric controls for the expanding and releasing of the jacks; two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners, with respect to each corner, means associated with that corner, whereby maximum expansion of the jack at that corner will lower the base by releasing the jack at one of the corners adjacent to the given corner, and will put an end to the expansion of the jack at the given corner; means whereby maximum contraction of the jack at the corner opposite to the given corner will render inoperative the first-mentioned effect of the last-mentioned means; means whereby the dangling of any jack, without contributing to the support of the base, will cause the expansion of that jack, and means automatically rendering all the foregoing means inoperative during propelling.

10. In combination: a base; four ground-engaging units; four jacks, one connected to and supported by each ground-engaging unit, and connected to and supporting the base; means to expand each jack; means to release each jack, so as to permit it to contract; electric controls 75

- for the expanding and releasing of the jacks; two level-responsive switch devices, each responsive to the difference in level of a pair of opposite corners of the base; each switch device being so coupled with the electric controls that a difference in level of a pair of opposite corners of the base will expand the jack at the lower of these two corners, and will release the jack at the higher of the two corners, with respect to each corner, means 5 associated with that corner, whereby maximum expansion of the jack at that corner will lower the base by releasing the jack at one of the corners adjacent to the given corner, and will put an end to the expansion of the jack at the 10 given corner; means whereby the dangling of any jack, without contributing to the support of the base, will cause the expansion of that jack, and means for optional manual control of the 15 expansion and releasing of each jack.
11. In combination: a base; a plurality of ground-engaging units; a plurality of jacks, one connected to and supported by each ground-engaging unit, and connected to and supporting the base; means to expand each jack; means to release each jack, so as to permit it to contract; 20
- 25

electric controls for the expanding and releasing of the jacks; two level-responsive switch devices, each responsive to a departure from level of one of a pair of normally horizontal lines in the base, at substantially right angles to each other; means whereby said controls automatically effect leveling of the base; and means whereby said controls automatically effect equalizing of the pressure on the supporting units. 5

12. In combination: a base; four ground-engaging units; four jacks, one connected to and supported by each ground-engaging unit, and connected to and supporting the base; means to expand each jack; means to release each jack, so as to permit it to contract; and, with respect 1 to each ground-engaging unit, a control mechanism, connected to two elements which tend to move relative to each other whenever and only when that unit dangles, this control mechanism being operable by that relative motion to positively actuate the expanding means of the jack at that corner, so that the jack will constitute a positive support for the base at that corner. 10 15 20
